AUTOMOBILE STEREO TAPE PLAY-BACK UNIT

Makoto Fujihara, Tokyo, Japan, assignor to Teikoku
Dempa Co., Ltd., Tokyo, Japan

Filed May 4, 1966, Ser. No. 2,158

Claims priority, application Japan Feb. 24, 1966

Term of patent 7 years

(Cl. D26—14)

FIG. 1

FIG. 2

FIG. 3

FIG - 4

FIG - 5

FIG - 6

FIG. 7

FIG. 8

FIG. 1 is a top view;

FIG. 2 is a front view;

FIG. 3 is a side elevation as seen from the right of FIG. 1;

FIG. 4 is a side elevation as seen from the left of FIG. 1;

FIG. 5 is a bottom view;

FIG. 6 is a rear view of my design.

FIG. 7 is a perspective view as seen from the top and front of FIG. 2; and

FIG. 8 is a perspective view as seen from the bottom and rear of FIG. 2.

The dominant features of the design reside in the portions shown in full lines in the drawing.

I claim:

The ornamental design for an automobile stereo tape play-back unit, substantially as shown and described.
